UNITED STATES PATENT OFFICE.

JARED MARIS, OF COLUMBUS, OHIO.

DESIGN FOR THE ORNAMENTATION OF FLANGES FOR HUBS.

SPECIFICATION forming part of Design No. 16,432, dated December 29, 1885.

Application filed October 21, 1885. Serial No. 180,554. Term of patent 14 years.

To all whom it may concern:

Be it known that I, JARED MARIS, a citizen of the United States, residing at Columbus, in the county of Franklin and State of Ohio, 5 have invented and produced a new and original Design for Wheel-Hubs, of which the following is the specification, reference being had to the accompanying drawings, forming part thereof.

10 In the accompanying drawings, Figure 1 represents a view in front elevation of hub embodying my invention, and Fig. 2 is a side view of one of the hub-flanges.

The leading feature of my design consists in 15 facets around the outer surface of one or both flanges of the hub. The facets *a*, which are either plane or slightly dished, extend from the outer edge or periphery of the flange *A* of the shell band *B* inwardly any desired distance, and may be in the form of equilateral

or isosceles triangles. The facets may join at their bases, or they may be slightly separated, if so desired.

The facets may be varied in size, and hence I do not restrict myself to the particular size 25 shown and described; but,

Having fully described my design, what I claim as new, and desire to secure by Letters Patent, is—

In a design for wheel-hubs, the ornamentation of the same, consisting in a flange at or approximately at right angles to the face of the hub, and a series of facets on the outer surface of the flange, at the periphery thereof, as shown and described. 30

JARED MARIS.
